Primary Examiner — Cynthia R Underwood(74) *Attorney, Agent, or Firm* — Kim IP Law Group LLC(57) **CLAIM**

The ornamental design for a peg hook and rack assembly, as shown and described.

DESCRIPTION

FIG. 1 is a front perspective view of a peg hook and rack assembly in accordance with the new design;

FIG. 2 is a right side view of the peg hook and rack assembly of FIG. 1;

FIG. 3 is a left side view of the peg hook and rack assembly of FIG. 1;

FIG. 4 is a rear view of the peg hook and rack assembly of FIG. 1;

FIG. 5 is a front view of the peg hook and rack assembly of FIG. 1;

FIG. 6 is a top plan view of the peg hook and rack assembly of FIG. 1; and,

FIG. 7 is a bottom plan view of the peg hook and rack assembly of FIG. 1.

The broken lines in FIGS. 1-3 and 5-7 illustrate portions of the peg hook and rack assembly which form no part of the claimed design.
